COSMETIC APPLICATOR

Charles A. Mureau, Los Angeles, Calif.

Application December 24, 1935, Serial No. 55,996

3 Claims. (Cl. 132—78.5)

This invention relates to a device for applying cosmetics and relates more particularly to a device for applying powdered rouge, face powder, etc. A general object of this invention is to provide a compact, attractive device for carrying and applying powdered rouge, face powder and the like.

Rouge in a powdered state has certain advantages over cream rouge or rouge in a cake form. Heretofore it has been difficult to carry powdered rouge in hand bags, etc. in a manner that permits of its ready easy application and the use of powdered rouge has been more or less restricted or curtailed for this reason.

Another object of this invention is to provide a practical, effective device for carrying and applying dry or powdered rouge and other comminuted cosmetics.

Another object of this invention is to provide a puff adapted to hold a supply of powdered rouge or face powder and that is such that the rouge or powder may be directly applied by the puff, the rouge or powder sifting from the puff when patted on the face.

Another object of this invention is to provide a device or puff that carries a supply of powdered rouge or other powdered cosmetic for application by the puff that is characterized by an observation opening or window by means of which the shade, quantity, quality and other characteristics of the contained cosmetic may be readily determined.

Another object of the invention is to provide a cosmetic applying puff of the character mentioned that includes a transparent closure or covering for the observation opening that is impervious to the cosmetic and lines the pocket of the puff to prevent loss of the cosmetic and soiling of the hands, etc.

Another object of the invention is to provide a cosmetic applying puff of the character mentioned that is easy and convenient to use and that is attractive in appearance.

A further object of the invention is to provide a cosmetic applicator of the character mentioned that is very simple and inexpensive of manufacture embodying a minimum number of simple, inexpensive parts.

The various objects and features of my invention will be fully understood from the following detailed description of a typical preferred form and application of my invention, throughout which description reference is made to the accompanying drawing, in which:

Fig. 1 is a side elevation of a case containing

the puff of the present invention. Fig. 2 is an enlarged vertical detailed sectional view of the case with the puff removed, being a view taken substantially as indicated by line 2—2 on Fig. 1. Fig. 3 is an enlarged fragmentary detailed sectional view taken substantially as indicated by line 3—3 on Fig. 2. Fig. 4 is an elevation view of the back of the puff provided by this invention. Fig. 5 is an enlarged vertical detailed sectional view taken as indicated by line 5—5 on Fig. 4. Fig. 6 is an enlarged fragmentary sectional view of the edge portion of the puff.

The cosmetic applying puff of the present invention includes, generally, a front element 10 permeable to the cosmetic, a back 11 secured to the front element 10 to provide a space or pocket 12 for carrying the cosmetic and having a window opening 13, and a transparent impermeable element 14 associated with the back 11 to close the opening 13 and prevent the loss of the cosmetic from the pocket 12.

The front element 10 is intended to be employed in applying the cosmetic contained in the pocket 12. The front element 10 is formed of material or fabric readily penetrated by the powdered cosmetic and its exposed surface is finished to effectively apply and distribute the cosmetic. The front element 10 preferably has a soft nap 15 on its outer side so that the puff may be patted against the skin to insure the sifting of the powdered cosmetic through the element 10 and to effect the desired distribution of the cosmetic. In the particular form of the invention illustrated the front element 10 is substantially disc shaped, it being understood that the element 10 may be of any other shape.

The back 11 is secured to the front element 10 in the manner to be hereinafter described to form or provide the pocket 12 for containing the cosmetic. The back 11 is preferably, though not necessarily, formed of a material substantially impervious to the powdered cosmetic. In practice I have found it desirable to form the back 11 of fabric treated or fabricated to be substantially impervious to the powder. The outer surface of the back 11 may have a satin finish or other finish to be attractive in appearance and may carry lettering indicating the make, quality, shade, etc. of the cosmetic contained in the pocket 12. In the preferred construction the back 11 is of the same shape and size as the front element 10. It is a feature of the invention that the back 11 has the observation opening or window opening 13 through which the cosmetic in the pocket 12

12 may be seen. The opening 13 may be shaped and located as desired. In the construction illustrated in the drawing the opening 13 is round and is centrally located in the back 11.

5 The transparent element 14 is provided to prevent the loss of the powdered cosmetic from the opening 13 and to line the back 11 to prevent the powder from sifting or penetrating through the back. The transparent element 11 10 is in the nature of a sheet of relatively thin transparent celluloid or similar material having a suitable degree of flexibility. In practice the transparent element 14 is of the same shape and size as the back 11 to lie against and line 15 the inner surface of the back. The transparent element 14 is arranged concentric with the back 11 to extend completely across and close the window opening 13.

In accordance with the invention the front 20 element 10, the back 11 and the transparent element 14 are secured together by a single means. Stitching 16 connects or secures together the peripheral edge portions of the front element 10, the back 11 and the transparent 25 element 14. The pocket 12 is provided or filled with a desired quantity of powder or powdered rouge and the element 10, the back 11, and the transparent element 14 are stitched together to close the pocket 12 and thus retain the cosmetic in the puff. The stitching 16 extends completely around the peripheral edge of the puff and is preferably such that it covers or binds the edges of the front element 10, the back 11 and the transparent element 14. The 30 stitching 16 secures together the front element 10, the back 11 and the transparent element 14 to provide a simple symmetrical unbroken cosmetic containing puff. The transparent element 14 arranged between the front element 10 and the back 11 and connected to them by the stitching 16 stiffens the puff to the desired extent and yet permits bending or flexing of the puff.

The invention provides a simple, effective 45 case C for the cosmetic containing puff. The case C comprises two sides S of fabric that are formed to be substantially impervious to the powdered cosmetic. The sides S of the case C each comprise two members 20 and 21 50 of fabric having treated or finished surfaces substantially impervious to powder. The members 20 and 21 of the sides S are arranged with their untreated or unfinished surfaces in abutment or facing each other so that the finished surfaces of the members line the opening 22 of the case and provide the case with finished 55 external surfaces. Stitching 23 connects or secures together the edge portions of the sides S. Where the puff is disc shaped as described above 60 the case C is also disc shaped and stitching 23 extends substantially 180° along its edge, leaving an opening 24 for admitting the puff. The stitching 23 in addition to securing together the sides S of the case binds the edges of the members 20 and 21 comprising the sides. Metal 65 clips 25 may be provided at the opposite ends of the line of stitching 23 to reinforce the case C and prevent loosening or unraveling of the stitching. The clips 25 are not essential and may or may not be used as desired.

70 It is believed that the utility and practicability of the cosmetic containing puff of the present invention will be readily apparent from the foregoing detailed description. The puff

is capable of holding a substantial supply of powdered rouge or other cosmetic in its pocket 12. The cosmetic may be readily applied by patting the skin with the front element 10 of the puff, the element 10 being penetrable by 5 the powdered cosmetic. The transparent element 14 lines the back 11 against the penetration or shifting of the cosmetic and stiffens the puff to some extent so that it may be conveniently used in applying the cosmetic. The transparent element 14 extends completely across and closes the window opening 13 preventing the escape of the powdered cosmetic from the pocket 12. As the element 14 is transparent the shade 10 and other characteristics of the cosmetic in the pocket 12 may be readily observed through the opening 13. Thus the cosmetic applying puff contains a supply of powdered cosmetic in a manner so that the cosmetic may be viewed 15 to determine its color and other characteristics. The single line of stitching 16 effectively and dependably ties together and connects the three parts 10, 11 and 14, comprising the puff and binds the otherwise exposed edges of the parts. When the puff is contained within the case C 20 the cosmetic contained within its pocket 12 is substantially prevented from sifting through the previous front element 10. The case C thus forms a simple effective device for carrying the cosmetic containing puff in a pocket book or 25 the like. The improved cosmetic containing puff of the present invention consists of only three simple parts and is very inexpensive of manufacture.

Having described only a typical preferred form 30 and application of my invention I do not wish to be limited or restricted to the specific details herein set forth, but wish to reserve to myself any variations or modifications that may appear to those skilled in the art or fall within the 35 scope of the following claims.

Having described my invention, I claim:

1. A device for applying a powdered cosmetic comprising a front permeable to the cosmetic, a back associated with the front to form a pocket 45 for carrying the cosmetic to be sifted through the front, the back having a window opening, a transparent element lining the back and closing the window opening against the loss of the cosmetic from the opening, and stitching securing together the front, back and transparent element.

2. A device for applying a powdered cosmetic comprising a front permeable to the cosmetic, a back associated with the front to form a pocket 55 for carrying the cosmetic to be sifted through the front, the back having a window opening, a transparent element impervious to the cosmetic arranged against the inner side of the back to extend across the window opening, and stitching 60 securing together the front, back and transparent element.

3. A powder puff including, a disc shaped fabric front permeable by powder, a disc shaped back impervious to the powder and related to the front to provide a space for carrying the powder, the back having a window opening, a disc shaped transparent element impervious to the powder and arranged against the inner side of the back to close the window opening, and stitching 65 securing together the peripheral edge portions of the front, back and element.
